DISPLAY BOX

Marguerite M. Seals, Long Beach, Calif.

Application October 11, 1952, Serial No. 21,800

Term of patent 14 years

(Cl. D58—11)

To all whom it may concern:

Be it known that I, Marguerite M. Seals, a citizen of the United States, residing at Long Beach, State of California, have invented a new, original, and ornamental Design for a Display Box, of which the following is a specification, reference being had to the accompanying drawing, forming a part hereof.

Figure 1 is a front perspective view of a display box, showing the top portion thereof in raised position embodying my new design;

Figure 2 is a rear perspective view thereof; and

Figure 3 is a rear perspective view of the box in closed position and taken on a reduced scale.

The dominant feature of my design resides in the portions shown in full lines.

I claim:

The ornamental design for a display box, as shown and described.
